BREECH-ACTION FOR FIREARMS.

1,344,911.

Specification of Letters Patent. Patented June 29, 1920.

Application filed March 24, 1915. Serial No. 16,599.

To all whom it may concern:

Be it known that I, ISAAC NEWTON LEWIS, a citizen of the United States of America, residing at 5 Adelphi Terrace, Strand, London, W. C., England, have invented certain new and useful Improvements in Breech-Actions for Firearms, of which the following is a specification.

This invention relates to breech actions for automatic and semi-automatic firearms, and the object of the present invention is to provide an improved breech action by which the breech may be opened and closed rapidly with a minimum of jar and shock and consequent wear of the moving parts.

The breech block of automatic firearms and especially those of the gas operated type, is very commonly locked in firing position by having a partial rotary movement imparted to it by means of the gas piston or other breech opening device. Now, it is clear that the time in which the unlocking operation may take place is very short and consequently the sudden overcoming of the inertia of a comparatively heavy breech block entails a great strain on the operating parts and also exerts a restraining influence on the rapidity of fire.

The object of the present invention is to so construct the breech mechanism that the main portion of the breech block does not have to be turned to effect the locking and unlocking operations which are effected by a relatively small and light locking piece capable of rotation relatively to the main portion of the breech block. The locking piece is so designed that it may have its weight and hence its inertia, reduced to a minimum without in any way sacrificing the necessary strength and reliability.

I preferably employ in connection with the improved breech block, a firing pin which is so arranged that its striking end cannot reach the cartridge cap until the breech block is properly locked in position.

Referring now to the accompanying drawings which show a convenient embodiment of my improved breech mechanism applied to a small arm of the gas operated type:

Figure 1 is a longitudinal sectional view of the breech portion of the rifle, showing the breech block in closed position;

Fig. 2 is a side view of the breech block with its locking nut removed.

Fig. 3 is a longitudinal sectional view of the breech block taken on the line 3—3 of Fig. 4, this view also showing the extractor in position;

Fig. 4 is an end view of the breech block;

Fig. 5 is a view of the breech block nut showing the inner end thereof and the lugs which engage with those on the breech block proper;

Fig. 6 is a side view of the nut;

Fig. 7 is a view of the outer end of the said nut.

Fig. 8 is a section thereof taken on the line 8—8 of Fig. 7.

Fig. 9 is a plan view on an enlarged scale of the cam piece which is carried upon the gas operated piston rod.

Fig. 10 is a sectional view thereof taken on the line 10—10 of Fig. 9;

Fig. 11 is a section on an enlarged scale on the line 11—11 of Fig. 1 through the receiver casing or body piece, the magazine and all removable parts being omitted, while

Fig. 12 is a similar view taken on the line 12—12 of Fig. 1.

In the drawings, *a* is the barrel, *b* the wooden barrel support or casing, and *c* is the body piece in which the breech block is adapted to reciprocate and which is provided with grooves 11 to receive lugs 10 on the breech block nut as hereafter more fully described.

The breech block is of peculiar character in that it is made up of two parts, a long tubular part 4, and a short tubular part 5 at the rear which I will call the "nut." The nut part 5 is connected to the tubular part 4 by means of locking lugs 6 upon a spigot provided on the part 4, these lugs being arranged to engage behind corresponding lugs 7 in the nut part. In the example shown the locking or unlocking of the two parts 4 and 5 is effected by a relative rotation of about one sixth of a revolution.

The part 4 of the breech block is provided with a projection 8 which is adapted to run in a slot 9 in the body piece *c* of the arm; in this way the part 4 cannot rotate but may only reciprocate in the body piece or receiver. The nut part 5 is provided with lugs 10 which are adapted to run (during the reciprocation of the breech block) in grooves 11 provided in the body-piece or receiver of the arm. When the breech block

is in closed position as in Fig. 1, however, the nut part 5 is situated in a space in the body piece or receiver of a diameter throughout as great as the depth of the 5 grooves 11 (as shown by the dotted circle 11' in Fig. 12) so that the nut can be rotated to bring its locking lugs in or out of register with the said grooves, in order to effect unlocking or locking of the breech 10 block. In the construction shown about one twelfth of a rotation of the nut is required for locking or unlocking so that the nut is not, by such action, unlocked from the part 4 of the breech block.

15 In order to effect the necessary rotation of the breech block nut for locking and unlocking the same the cam piece 3 is provided. This cam piece is detachably connected to a piston rod 3' by suitable locking lugs and on its under side is provided with a cam slot 13 which is adapted to engage a simple projecting piece 14 on the breech block nut. When the breech block is in closed position the projection 14 lies 20 in the rear end of the cam slot, as will be understood from Fig. 1 and in this position the lugs 10 on the nut are out of register with the grooves 11 in the body piece, or in other words the breech block is locked 25 against backward movement. Upon the cam piece moving rearwardly, either by the action of the gases on the piston rod 3' or by pulling on a handle 15 provided for the purpose, the cam slot 13 will cause the 30 nut to rotate in a counter clockwise direction (looking toward the muzzle of the rifle) to a sufficient extent to bring the lugs 10 into register with the grooves 11. The breech block is now unlocked and the continued rearward movement of the cam piece 40 will carry back the entire breech block so as to open the breech.

It will be understood that the piston rod 3' is fitted with a piston at its forward end 45 working in a suitable chamber having access to the barrel in the well known manner, so that when a cartridge has been fired some of the discharge gases enter the chamber and drive back the piston. The stem of the 50 handle 15 projects through a suitable slot in the side of the casing c' covering the rear portion of the receiver, so that the breech may be opened by hand when desired.

55 The breech block is provided with a suitable extractor 16 which fits into a recess 16' in the side of the breech block and has a hook-like free end 16'' which engages the rim of a cartridge in the well known manner. It is made from spring steel and is sprung into place with its rear edges 17 beneath the overhanging ledge 18 on the breech block, and with the button 19 engaging the aperture 20 in the breech block.

65 The extractor is provided on the right

hand side of the breech block locking toward the muzzle of the rifle, and as the breech block is retracted the spent cartridge case is drawn out of the chamber by the extractor and when clear thereof is tipped out 70 of the body of the rifle through an opening 20' (see Fig. 11). To insure that this tipping action shall take place a pin is provided on the inner surface of the body piece opposite the opening which pin is accommodated in a slot 22 in the breech block. When the breech block has moved back far enough the base of the cartridge opposite the extractor is struck by the pin and the empty case is forcibly thrown through the 80 opening 20'. The location of the pin is shown at 23 in dotted lines in Fig. 3.

In order to fire the cartridges a firing pin 24 is employed passing through a suitable aperture in the breech block and provided 85 in the rear of the nut with a plate 25 the lower portion of which is shaped to run in the slot 26 in the body piece c so that it cannot rotate. The forward side of this plate 25 is provided with two projections 27, 90 which, when the nut is in correctly locked position, lie directly in rear of two depressions 28 in the rear side of the nut (see Fig. 7). By these means the firing pin can only move forward sufficiently to fire the cartridge if the breech block is locked, otherwise the forward movement of the pin will be arrested by the engagement of the projections on the plate with the rear face of the nut. Moreover the action of rotating the 100 nut to unlock the breech at once draws back the end of the firing pin from the cartridge case. In order to keep the firing pin in place it is provided with a groove at 29 adapted to receive a split spring ring 30. This ring 105 may be removed or placed in position when the nut is removed from the part 4 of the breech block as shown in Fig. 8, but when the parts are assembled the spigot piece on the part 4 will enter the hollow space in the 110 nut surrounding the split ring and prevent any chance of its displacement.

The firing pin is operated to fire the cartridges by a striker 31 extending upwardly 115 through the slot 26 and carried upon a rod 32 which extends into a tube 33 in the stock 34, the striker being urged forwardly by a spring 35 located behind it. The striker 31 is shown in cocked position in Fig. 1 it being held in this position by the sear 36. 120 Upon pressing the trigger 37 the sear is depressed and the striker, now being free, moves forward under the action of the spring 35 until it strikes the plate 25 on the firing pin 24. When the breech block moves rearwardly in the manner already described it carries with it the striker 31, but upon the return of the breech block under the action of the spring 35 and a spring 38 located 125 around the piston rod 3' and operating be- 130

- tween the piston at the forward end thereof and a stationary washer 39, the striker will be arrested by the sear 36 in the position shown in Fig. 1 ready for firing the next 5 shot when the trigger is again pressed. As the details of the firing mechanism just described form no part of the present invention further description thereof is deemed unnecessary.
- 10 It is to be particularly observed that by employing a simple part on the "nut" or locking piece 5, which part may be a mere projection and providing the necessary means for rotating the locking piece, viz: the 15 cam groove 13, upon the operating part of the breech mechanism, the "nut" or locking piece can be made of only sufficient dimensions to have the requisite strength and rigidity, whereas if the cam groove were to 20 be provided in the "nut" the dimensions of the latter and hence its weight and inertia would be seriously increased.

Having described the invention what I claim as new and desire to secure by Letters 25 Patent is:—

1. Breech mechanism for firearms, comprising a breech block consisting of a main portion and a locking piece carried thereby, said main portion and locking piece having 30 coöperating parts interlocked by a predetermined relative rotational movement of the main portion and locking piece, and movable breech opening and closing means co-acting with said locking piece and adapted 35 to impart rotational locking and unlocking movements thereto less in extent than the aforesaid predetermined movement, said locking piece when in locking position co-acting with parts on the breech chamber.
- 40 2. Breech mechanism for firearms, comprising a breech block having a reduced extension at the rear end thereof, a relatively short locking piece abutting against the rear face of said block and rotatable on said extension, said locking piece and block having integral co-acting interlocking means, and movable breech opening and closing means co-acting with said locking piece to impart 45 rotational locking and unlocking movements thereto, to cause the same to engage with and disengage from locking parts on the breech chamber.

- 50 3. Breech mechanism for firearms, comprising a breech block consisting of a main portion and a locking piece carried thereby and provided with a projection, said main portion and locking piece having coöperating parts interlocked by a predetermined relative rotational movement of the main 55 portion and locking piece, and movable breech opening and closing means provided with cam means co-acting with the projection on the locking piece to impart rotational locking and unlocking movements 60 thereto less in extent than the aforesaid pre-

determined movement, said locking piece when in locking position co-acting with parts on the breech chamber.

4. Breech mechanism for firearms, comprising a breech block having a reduced extension at the rear end thereof, a relatively short locking piece abutting against the rear face of said block and rotatable on said extension and provided with a projection, said locking piece and block having integral angularly spaced co-acting interlocking means, and movable breech opening and closing means provided with cam means co-acting with the projection on the locking piece to impart rotational locking and unlocking movements thereto, to cause the same to engage with and disengage from locking parts on the breech chamber.

5. Breech mechanism for firearms, comprising a breech block having a reduced extension at the rear end thereof, a relatively short locking piece abutting against the rear face of said block and rotatable on said extension, said extension and locking piece having coöperating parts interlocked by a predetermined relative rotation of the locking piece and main portion, and movable breech opening and closing means co-acting with said locking piece to impart 85 rotational locking and unlocking movements thereto less in extent than said predetermined movement, to cause the same to engage with and disengage from locking parts on the breech chamber.

6. Breech mechanism for firearms, comprising a breech block consisting of a main portion and a relatively short locking piece carried thereby and rotatable thereon and provided with a radial projection, said locking piece and block having integral angularly spaced co-acting interlocking means, a gas operated piston, and a member directly connected to the rear end of said piston, said member having cam means directly co-acting with the projection on the locking 105 piece to effect rotational locking and unlocking movements of said locking piece relatively to locking parts on the breech chamber.

7. Breech mechanism for firearms, comprising a breech block, a relatively short locking piece of substantially the same diameter as said breech block and abutting against the rear face of said block, coöperating parts integral with said block and locking piece for connecting the locking piece to the block to move axially therewith, and movable breech opening and closing means co-acting with said locking piece to impart 115 rotational locking and unlocking movements thereto to cause the same to engage with and disengage from locking parts on the breech chamber.

8. Breech mechanism for fixed barrel automatic and semiautomatic firearms, com- 120

prising a movable breech opening device operated by a gas impulse from the muzzle end, a breech block consisting of a main portion and a relatively small and light nut or locking piece capable of rotation relatively to the main portion of the breech block and carried on its rear end, means carried upon said movable breech opening device for rotating said nut or locking piece, locking and 10 unlocking of the breech block being effected by a rotational movement of the nut or locking piece alone, and a firing pin in the breech block, the firing pin and the nut or locking piece of the breech block having co- 15 operating projections and recesses whereby the firing pin can only move forward to fire a cartridge when the nut or locking piece is in properly locked condition.

9. Breech mechanism for automatic and 20 semiautomatic firearms, comprising a movable breech opening device and a breech block consisting of a main portion and a relatively small and light nut or locking piece capable of rotation relatively to the main portion of the breech block and carried at the rear end thereof, said breech block parts having rotationally engaging parts remaining in engagement after rotational disengagement of the locking piece 25 from the breech and disengageable from one another by a further relative rotation.

10. Breech mechanism for fixed barrel automatic and semi-automatic firearms, comprising a movable breech opening device operated by a gas impulse from the muzzle 30 end and a breech block consisting of a main portion and a relatively small and light nut or locking piece capable of rotation relatively to the main portion of the breech block, and to the fixed breech chamber, said parts co-operating to effect locking and unlocking of the breech block by a rotational movement of the nut or locking piece alone by means carried upon the said movable 35 breech opening device, and a firing pin in the breech block located in relation to the said nut or locking piece by a device held in

place by assembly with the breech block parts.

• 11. A breech block for a firearm, comprising a main portion and a locking piece rotatably carried thereby, said main portion and locking piece having co-operating parts interlocked by a predetermined relative angular movement of the main portion and locking piece less than a complete rotation but greater in extent than the rotational locking and unlocking movements of said locking piece, and said locking piece having means for co-operating with operating 60 means.

12. A breech block for a firearm, comprising a main portion and a relatively short locking piece of substantially the same diameter as said main portion abutting 65 against the rear face thereof and rotatable relatively thereto, said main portion and locking piece having angularly spaced co-operating parts integral therewith for connecting the locking piece to the main portion by a relative axial movement and a relative rotative movement to interlock said parts.

13. A breech block for a firearm, comprising a main portion having a reduced extension at the rear end thereof and a relatively short locking piece abutting against the rear face of said main portion and rotatable on said extension, said locking piece and extension having integral angularly 75 spaced co-acting interlocking means interlocked by relative rotative movement of greater extent than the locking and unlocking movements of said locking piece, and said locking piece having means for co-operating with operating means.

In testimony whereof I have signed my name to this specification in the presence of two subscribing witnesses.

ISAAC NEWTON LEWIS.
